(57) **CLAIM**

The ornamental design for a bread sling, as shown and described.

DESCRIPTION

FIG. 1 is a top front perspective view of a bread sling, showing our new design;

FIG. 2 is a top plan view thereof;

FIG. 3 is a bottom plan view thereof;

FIG. 4 is a front elevation view thereof, the rear elevation view being an identical image thereof; and,

FIG. 5 is a right-side elevation view thereof, the left-side elevation view being an identical image thereof.

The evenly spaced broken lines shown in the drawings depict portions of the bread sling that form no part of the claimed design.

The shade lines in the drawings do not illustrate material, surface ornamentation, or surface decoration.

The use of stippling indicates a contrasting appearance with the adjacent line-shaded portions of the bread sling.

The circles circumscribed by the stippling are circular openings that have a uniform circumference as they extend from the claimed flat top surface through to the disclaimed bottom surface.
